FISH LURE

Chris Ralph Handkamer, Winnipeg, Manitoba,
Canada

Application December 14, 1951, Serial No. 17,728

Term of patent 14 years

(Cl. D31—4)

To all whom it may concern:

Be it known that I, Chris Ralph Handkamer, a citizen of Canada, residing at 408 McKenzie Street, city of Winnipeg, in the Province of Manitoba, Canada, have invented a new, original, and ornamental Design for a Fish Lure, of which the following is the specification, reference being had to the accompanying drawings, forming part thereof.

Figure 1 is a perspective view of the fish lure, illustrating my new design.

Figure 2 is a side view of the fish lure.

The side opposite that shown in Figure 2 is substantially like the one shown.

I claim:

The ornamental design for a fish lure, substantially as shown and described.

CHRIS RALPH HANDKAMER.
